UNITED STATES PATENT OFFICE.

DAVID LEVIGTON, OF NEW YORK, N. Y.

GARTER AND METHOD OF MAKING THE SAME.

Application filed August 4, 1922. Serial No. 579,643.

This invention relates to a class of articles for wear by persons.

My invention has for its object primarily to provide a garter for supporting stockings on the legs of the wearer against tendency to accidentally lower, and which is of a type wherein is provided a flexible strap or strip having on one of its ends an integral pad of a substantially pentagon or 10 triangular shape formed by folding parts of one end of the strap in overlapping arrangement whereby a clasp for detachably fastening the garter to a stocking may be mounted on the pad. The provision of the 15 pad in this manner serves to greatly lessen the cost of manufacturing the garter by overcoming the requirement of making separate clasp-pads and attaching them to the garter straps as is incident to present meth- 20 ods.

Another object of the invention is to provide a fastener which is adjustably movable on the second end of the strap so that the 25 adjustable loop commonly used in garters on the second ends of their straps for varying the circumference of the garters may be dispensed with.

A further object of the invention is to provide a garter of a simple and efficient 30 form which may be made of appropriate material in various sizes.

With these and other objects in view, the 35 invention will be hereinafter more fully explained with reference to the accompanying drawing forming a part of this specification in which similar characters of reference indicate corresponding parts in all the views, and will then be pointed out in the 40 claims at the end of the description.

In the drawing, Figure 1 is a fragmentary view showing a person's leg with a stocking supported by one form of my improved 45 garter.

Fig. 2 is an elevation, partly broken away, 50 of the garter, and

Fig. 3 is an enlarged fragmentary view taken on the line 3—3 of Fig. 2.

The garter has a strap or strip member 10 which may be of elastic or non-elastic 55 webbing, or of leather or other appropriate flexible material of a suitable width and of a length adapted to be applied in encircling fashion on the leg, as A, of a person when the garter is used for detachably supporting a stocking, as B.

On one end of the strap 10 is a pad mem-

ber, as 11, which is substantially the shape of a pentagon, or may be approximately triangular, and this pad is integrally formed on the strap by folding parts of one end 60 portion, as 12, of the strap upwardly on a relative incline, as at 13, so that the folded part overlaps one face of the strap. The folded part 13 is then folded downwardly, as at 14, on a relative incline crosswise so 65 that it overlaps the other face of the strap, and the free end part, as 15, of the strap is folded over the end portion 12 as well as being disposed between the overlapping portion 13 and the portion 12 of the strap. 70 These overlapping folds of the pad member may be stitched together, as at 16, and on the central part of one face of the pad is a loop, as 17, with a depending short strip, as 18. The loop 17 may be of metal and 75 the strip 18 may be of cloth, and on these parts is provided a clasp, as 19, of a form commonly used in conjunction with garters, composed of a metal loop, as 20, which is held to the strip 18 so that its lower end 80 is disposed toward the lower end of the strip. On the strip 18 is also a button or knob 21 which, when the garter is detachably fastened to a stocking, is disposed under the upper edge of the stocking with 85 the loop 20 being exteriorly of the stocking. By forcing the button 21 with part of the stocking lying thereon through the loop 20 and then moving the loop 20 upwardly the button and stocking will be 90 removably clamped as is incident with the well known functioning of this type of clasp.

The part of the strap 10 other than the 95 pad member 11 is adapted to be arranged in encircling fashion on the leg of the wearer of the garter following attaching the clasp 19, as explained, to the stocking, and on the second end portion of the strap is a fastener, as 22, which is adjustably movable 100 for reducing and enlarging the circumference of the strap when surrounding the leg of the wearer. The fastener 22 is preferably of a form having a plate 23 with two apertured lugs or eyes 24, 25 protruding from 105 an end above one of its faces, and these eyes are spaced apart so that the strap 10 is disposed therebetween. In the eyes 24, 25, are rotatably held the lugs or pins of a well known form of clamp lever 27 having a 110 downwardly inclined portion with a toothed edge, as 28, normally in removable engage-

ment with the part of the strap lying upon the plate 23 between the eyes 24, 25 for clamping the plate and strap together, and extending angularly from the toothed portion 28 is a finger piece, as 29, which is normally disposed toward and upon the part of the strap resting on the plate 23 when the teeth are in engagement with the strip. As is usual with this form of clamp when the finger piece 29 is swung upwardly from the strap 10 the toothed portion 28 will be disengaged from the strap which in turn will release the clamp for being adjustably positioned on the strap toward and from the pad member 11 to lengthen or shorten the space between the fastener and the pad member. On the loop 17 is provided a button or knob, as 30, and the plate 23 has opposite to its eyes 24 and 25 an extension, as 31, in the free end part of which is a hole or opening 32 of a size adapted to fit removably over and upon the button 30 so that when the strap member is arranged around the leg of the wearer it will be detachably fastened to the button. The garter will thereby be removably held on the leg of the wearer, and the provision of this form of the fastener 22 enables dispensing with the use of the adjusting loop provided on the ends of the strip member of ordinary types of garters of this class.

In the foregoing description, I have embodied the preferred form of my invention, but I do not wish to be understood as limiting myself thereto, as I am aware that modifications may be made therein without de-

parting from the principle or sacrificing any of the advantages of this invention; therefore, I reserve to myself the right to make such changes as fairly fall within the scope 40 thereof.

Having thus described my invention, I claim as new and desire to secure by Letters Patent:

1. The method of making parts of a garter, which consists in folding one end portion of a flexible strip on an upward incline on one face of itself, folding an adjacent portion of the strip on a downward incline across its opposite face, then inserting the 50 adjoining free end of the strip between the lapping portions, stitching the edges of the overlapping portions together to form a pad, and providing means on the pad for supporting a clasp.

2. In a garter, the combination of a flexible strip, a pad member integral with one end of the strip, including one end portion of the strip overlapping one face thereof on an upward relative incline, a second portion of the strip overlapping the folded part on a relative downward incline crosswise of its opposite face, and the adjacent free end part of the strip disposed between the overlapping portions, said overlapping portions having their edges stitched together, and means on the pad member for supporting a clasp.

This specification signed and witnessed the 3d day of August, A. D. 1922.

DAVID LEVIGTON.
